COMBINED GROUND-FAULT INTERRUPTER AND RECEPTACLE

Arthur J. Pulos, Syracuse, N.Y., assignor to
Pass & Seymour, Inc., Syracuse, N.Y.

Filed Dec. 27, 1972, Ser. No. 319,012

Term of patent 14 years

Int. Cl. D13—03

U.S. Cl. D26—13 R

FIG. 1.

FIG. 2.

FIG. 3.

FIG. 4.

FIG. 5.

FIG. 1 is a front elevational view of the combined ground-fault interrupter and receptacle with the mounting strap shown in dotted lines for illustrative purposes only.

FIG. 2 is a side elevational view.

FIG. 3 is a rear elevational view.

FIG. 4 is a top plan view, and

FIG. 5 is a front perspective view.

I claim:

The ornamental design for a combined ground-fault interrupter and receptacle, as shown and described.
